UNITED STATES PATENT OFFICE.

ETIENNE DE SAPTES, OF NEW YORK, N. Y., ASSIGNOR TO GEORGE REISSER,
OF SAME PLACE.

DESIGN FOR A MONUMENT.

SPECIFICATION forming part of Design No. 22,612, dated July 11, 1893.

Application filed June 2, 1893. Serial No. 476,401. Term of patent 7 years.

To all whom it may concern:

Be it known that I, ETIENNE DE SAPTES, of the city, county, and State of New York, have invented and produced a new and original 5 Design for Monuments, of which the following is a specification, reference being had to the accompanying drawings, forming part thereof.

The figure of the drawing is an elevation 10 of a monument embodying my design.

The leading feature of my design consists in the base having brackets at the sides of the monument, the vases supported thereon, the niche and the statue bracket.

15 Referring by letter to the drawing, A, designates the base of the monument, and B, the pedestal thereon. The pedestal is shown as

having the florated designs a , a' . Brackets A', extend outward from the pedestal and upon these brackets vases B' are supported. 20 C, is the shaft mounted on the pedestal. This shaft has corner pillars c, a niche c', and a bracket c², upon which a figure or statue is mounted. The capitals of the pillars are shown as of the volute type and the frieze 25 has festoons d, of flowers.

What I claim as my invention is—

The design for a monument, substantially as shown and described.

ETIENNE DE SAPTES.
